UNITED STATES PATENT OFFICE.

GEORGE L. HEIDLER, OF YORK, PENNSYLVANIA.

IMPROVEMENT IN HORSE-RAKES.

Specification forming part of Letters Patent No. 56,222, dated July 10, 1866.

To all whom it may concern:

Be it known that I, GEORGE L. HEIDLER, of York, county of York, and State of Pennsylvania, have invented new and useful Improvements in Horse-Rakes; and I do hereby declare the following to be a clear and exact description thereof, reference being had to the accompanying drawings, and to the letters of reference marked thereon, making a part of this specification.

The nature of my invention consists in the arrangement and combination of the independent teeth attached to the head in front of the carriage-axle with the pressure-board to guide and press the teeth to the ground.

Figure 1 represents a top view of the machine; Fig. 2, an end view; Fig. 3, a section of pressure-board.

A represents the driver's seat; B, the carriage-axle; C, the shafts; D, the lever by which the teeth E are raised and lowered.

The teeth E are attached to ferrules on a head in front of the axle B.

At the back of the axle I have a pressure-board, H, formed of a frame extending across the machine the whole width, having rods J at equal distances apart, between which the teeth rest, and are pressed to the ground by the operation of the lever D.

K are straight cleaners attached to a bar on the back end of the shafts C.

What I claim as my invention, and desire to secure by Letters Patent, is—

The arrangement of the independent teeth attached to the head in front of the axle and the pressure-board to guide and press the teeth to the ground, constructed and operating as herein described.

GEORGE L. HEIDLER.
